UNITED STATES PATENT OFFICE.

JOHN R. HIGHTOWER AND WILLIAM A. HOOVER, OF KNOXVILLE, TENNESSEE.

STEP-ILLUMINATING LIGHT.

Application filed July 3, 1925. Serial No. 41,290.

This invention relates to illumination and section of the pilot of such a locomotive has special reference to locomotive illuminating means particularly designed to afford illumination to the steps and foot boards 5 of locomotives, tenders and the like.

It is a well known fact that train men, yard men and other railway employees constantly get on and off locomotives and tenders while the latter are in motion. This 10 is especially true of yard men who are in the habit of "jumping" yard engines in their work around the yard. Such engines and their tenders are usually provided with front and rear running boards or steps which extend transversely across between the rails of the track and the men jump the engine by standing between the rails in front of the approaching engine, lifting one foot and placing on the step as the engine rolls toward them. Obviously a mis-step, as frequently 20 happens at night when the step cannot be clearly seen, frequently results in serious injury to the employee and sometimes in death.

25 Heretofore, no attempt has been made to overcome this lack of illumination at this critical place except by lantern or the like in the employee's possession and this is ineffective because the location of the step can be 30 only assured when the engine has approached too close to the employee to enable him to avoid the accident.

The principal and most important objects 35 of the present invention is to provide a novel arrangement of illumination for such purposes wherein the steps will be properly rendered visible at all times and wherein the illuminating means will be positioned to be protected from accident and from throwing 40 a glare in the employee's eyes and thus blinding him and making accident more liable.

With the above and other objects in view as will be hereinafter apparent, the invention 45 consists in general of certain novel details of construction and combinations of parts hereinafter fully described, illustrated in the accompanying drawings and specifically claimed.

50 In the accompanying drawings like characters of reference indicate like parts in the several views, and:

Figure 1 is a side elevation of an ordinary road locomotive equipped with this invention.

55 Figure 2 is an enlarged detail partly in

showing the lighting arrangement.

Figure 3 is a similar view showing the cab step illumination. 60

Figure 4 is a front elevation of a yard engine equipped with this invention.

Figure 5 is a rear view of a yard tender similarly equipped.

Figure 6 is an enlarged detail section 65 through an end sill or bumper showing one arrangement of the lamp.

Figure 7 is a similar view showing a modification.

Figure 8 is a similar view showing a second modification. 70

In the present illustration as shown in the drawings several modifications of the invention are disclosed but in each case it will be seen that the invention improves not 75 only a mere illuminating lamp but also the combination of such a lamp and a portion of the engine, the lamp being so arranged that is supported and protected against injury. This is a very important feature of such an 80

invention by reason of the fact that it is necessary, in order to properly illuminate the foot-boards or running-boards, the lamps being placed low down on the engine in positions where they would be constantly 85 liable to be struck by an employee in getting on or off the engine unless provision was made to properly protect the lamp and protect it against such injury. Furthermore, unless such provision was made not 90

only would the lamp be liable to injury but the employee hitting the lamp would be apt to injure himself. This is particularly true when such a lamp is used on the end sill or bumper of a yard engine or tender and it is 95 to be understood in this specification that where reference is made to an end sill for rolling stock, this expression is intended to include the bumper beam of a locomotive and the end sill of a tender. 100

Bearing these facts in mind it will be seen from the illustrations in the accompanying drawings that in Figure 1 there is disclosed a locomotive 10 of the ordinary road type and that this locomotive is provided with a pilot 11 having steps 12. Also the locomotive is provided with a rear step 13 and a rear end sill 14 as well as a bumper or front end sill 15. Similarly in Figures 4 and 5 there is disclosed a yard locomotive 16 having a bumper or front end sill 17 and a tender 18 having an end sill 19. Both 105 110

the locomotive and tender are provided with steps or running-boards 20 supported by brackets 21 from the end sills. The lamp may be either supported beneath the end sills as shown in Figures 4 and 5 or supported against the end sills as shown in Figure 1. When supported beneath the end sills it is preferred that a bracket 21 be bolted beneath the sill and that an adjustable arm 22 held by an adjustable bolt and nut 23 be mounted pivotally on the bracket and carry a hood 24 wherein is the lamp 25, suitable wiring connections of any desired type leading to said lamp.

15 In cases where the lamp is supported against the bumper the bracket is preferably made of L-shape as shown at 26 in Figures 6 and 7 and carries the hood 27 which lies against the face of the bumper on one side so that it is firmly supported thereby, a pocket 28 being provided in some instances as shown in Figure 7. In such a hood there is supported the usual lamp 29. It will be observed that these lamps are all in such a position that the hood acts as a reflector to direct the light rays downwardly onto the steps and to prevent any of the light rays striking the eye of the employee as he stands in front of or at the side of the engine.

20 Thus the steps are thoroughly illuminated while at the same time the employee is not

blinded by the light and the accidents that are so liable to happen through the employee not seeing the step will be entirely eliminated.

35

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come 40 within the scope claimed.

45

Having thus described the invention, what is claimed as new, is:

In combination with a rolling stock bumper and a step supported below said bumper, said bumper having a pocket in the vertical face of the bumper adjacent the step and inclined downwardly toward the step; of a lamp hood fitted in said pocket above the lower edge of the bumper, said hood constituting a reflector from the lamp to direct rays from the lamp onto said step.

50

In testimony whereof we affix our signatures.

JOHN R. HIGHTOWER.
WILLIAM A. HOOPER.
